DISPLAY PACKAGE OF TOILET ARTICLES

Alan B. Lowry, Canton, Mass., assignor to The Gillette Company, Boston, Mass., a corporation of Delaware

Filed Mar. 11, 1965, Ser. No. 84,217

Term of patent 14 years

(Cl. D58—2)

FIG. 1

FIG. 3

FIG. 1 is a top plan view of a display package of toilet articles, showing my new design;

FIG. 2 is a front elevational view; and

FIG. 3 is a side elevational view thereof looking from the right of FIG. 2, the other side being a mirror image thereof.

The back of the case is plain.

The dominant features of my design reside in the portion shown in full lines.

I claim:

The ornamental design for a display package of toilet articles, substantially as shown and described.
